[57] **CLAIM**

The ornamental design for a bike bottle, as shown and described.

DESCRIPTION

FIG. 1 is a perspective view of a bike bottle incorporating the design of our invention, showing the pivotal closure in the closed position;

FIG. 2 is a front elevational view thereof;

FIG. 3 is a left side elevational view thereof, with the right side being a mirror image;

FIG. 4 is a rear elevational view thereof;

FIG. 5 is a top plan view thereof;

FIG. 6 is a bottom plan view thereof;

FIG. 7 is a perspective view of the bike bottle design of FIG. 1, showing the pivotal closure in the open condition;

FIG. 8 is a front elevational view thereof;

FIG. 9 is a left side elevational view thereof, with the right side being a mirror image;

FIG. 10 is a rear elevational view thereof;

FIG. 11 is a top plan view thereof; and,

FIG. 12 is a bottom plan view thereof.

The phantom lines (used for convenience of illustration) shown in FIGS. 7-11 for the bike bottle with the closure in the open condition depict the body of the bike bottle which is identical to that shown in FIGS. 1-6, respectively, for the bike bottle with the closure in the closed condition.
